UNITED STATES PATENT OFFICE

117,153

DESIGN FOR A CENTRIFUGAL PUMP AND MOTOR UNIT

Fred Stadelhofer, Berkeley, Calif.

Application August 28, 1939, Serial No. 86,911

Term of patent 7 years

To all whom it may concern:

Be it known that I, Fred Stadelhofer, a citizen of the United States, residing at Berkeley, in the county of Alameda and State of California, have invented a new, original, and ornamental Design for a Centrifugal Pump and Motor Unit, of which the following is a specification, reference being had to the accompanying drawing, forming part thereof.

Fig. 1 is a front elevation of a centrifugal pump and motor unit, showing my new design.

Fig. 2 is a side elevation;

Fig. 3 is a rear elevation; and

Fig. 4 is a top plan view, of Fig. 1.

I claim:

The ornamental design for a centrifugal pump and motor unit, as shown.

FRED STADELHOFER.
